(57) **CLAIM**

The ornamental design for a soap dispenser, as shown and described.

DESCRIPTION

FIG. 1 is a perspective view of a first embodiment of a soap dispenser according to our design;

FIG. 2 is a front elevational view thereof;

FIG. 3 is a right side view and a left side view is a mirror image thereof;

FIG. 4 is a top view thereof; and,

FIG. 5 is a bottom view thereof.

The broken lines shown in the figures represent portions of a soap dispenser that form no part of the claimed design.
